CLAIM

The ornamental design for a pet door, as shown and described.

DESCRIPTION

FIG. 1 is a first perspective view of a pet door showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1;

FIG. 11 is an enlarged view of the selected portion 11 in FIG. 1; and,

FIG. 12 is an enlarged view of the selected portion 12 in FIG. 2.

The broken lines shown in the drawings depict portions of the pet door that form no part of the claimed design. The dot-dash-dot broken lines are for call outs of enlarged sections of the article and form not part of the claimed design.

1 Claim, 12 Drawing Sheets
